UNITED STATES PATENT OFFICE.

AXEL I. S. HALVORSEN, OF ALBANY, INDIANA, ASSIGNOR TO McCORMICK BROS. COMPANY, OF ALBANY, INDIANA, A CORPORATION OF INDIANA.

SUPPORT FOR FLEXIBLE DOORS OF KITCHEN CABINETS.

Application filed May 14, 1926. Serial No. 109,083.

This invention relates to supporting means for flexible doors, composed of slats, used in kitchen cabinets and the like. Generally, the devices used for receiving the doors are grooved plates extending rearwardly from the doorway, across the compartment having the flexible door. Where these devices are placed in the upper part of the compartment, the door, when raised, extends across the top of the compartment and prevents the insertion of fittings into the compartment through its top. To obviate this difficulty, the door receiving devices are in some cabinets arranged beneath the base of the compartment, and the door is lowered to open the compartment instead of being raised.

In my invention, I have provided door supporting devices which occupy small space at the front of the compartment, near its top, and the door, when raised, coils into these devices and does not extend across the compartment, making it possible for fittings to be inserted into the compartment through its top, if desired. The door supporting means comprises a pair of flat metal disks, secured to the sides of the compartment, each disk having a central boss and a surrounding arcuate flange, the latter spaced from the former to provide room for the edge of the door to coil around the boss and the ends of the flange terminating at the opposite walls of the adjacent door guide in the cabinet, so that when the door is raised, its edges pass from the door guides into these supports and the door coils compactly in the upper forward part of the compartment, leaving an unobstructed space at the rear.

In the accompanying drawing, which illustrates my invention,

Fig. 1 is a vertical section, taken from front to rear, through part of a kitchen cabinet equipped with my improved door supports;

Fig. 2 is a horizontal section on the line 2-2 of Fig. 1;

Fig. 3 is an enlarged detail view of the support and adjacent parts shown in Fig. 4, the door being shown partly coiled within the support;

Fig. 4 is a view similar to that shown in Fig. 3, but illustrating a support having a larger central boss and suitable for doors having relatively thin slats; and,

Fig. 5 is a central section through a modified form of support, having a roller which constitutes a central boss of the support.

Referring to Figs. 1 to 3, inclusive, of the drawing, *a* represents a compartment of a kitchen cabinet having at its front side a doorway which is adapted to be opened and closed by a door *b*, composed of a plurality of slats 1, flexibly connected together, the ends of the slats fitting, in the usual manner, within guide grooves 2, formed at the sides of the doorway by outer and inner strips 3 and 4. To the side walls 5 and 6 of the casing, adjacent the upper ends of the guide grooves, are secured the door supports *c* and *c'*, respectively. As shown, the door support *c* comprises a flat circular plate 7, having a central boss 9, struck up from the body of the plate, and an outer arcuate flange 10. The inner guide 4 is shorter than the outer guide strip, and one end 10^a of the flange on the door support is turned outwardly and forms a lip which rests upon the top of the strip 4. The other end 10^b of the arcuate flange is shown resting against a cross-piece 3^a, the inner face of which is flush with the inner face of the strip 3. Thus, the slot or opening between the ends of the flange extends across the upper end of the groove 2. The door enters the support tangentially through the slot between the ends of the flange. The end 10^a of the flange is set back a little from the adjacent face of the guide groove, so that the flange will not engage the door. The plates or bases 7 of the supports are provided with suitably spaced openings to receive screws 11 by which the supports may be secured to the sides of the casing.

The supports *c* and *c'*, on the opposite sides of the casing, are alike in all respects except that one being at the right side of the casing and the other being at the left, the support *c'* is inverted with respect to the support *c*, and this makes it necessary to turn outwardly the end of the flange on the support *c'* which corresponds with the end 10^b on the support *c*. This outwardly turned end on the support *c'* is shown at 10^c resting on the inner guide 4 in Fig. 2.

The door is provided with the usual knob 12, on a cross-piece 13 at the lower end of the door, and by raising this knob the upper end of the door will be guided by the flanges 11.

of the supports until the end slat meets the slats entering the supports, and the end slats will then be carried upward around the bosses and the door will coil around the 5 bosses, as illustrated in Fig. 3.

The slats of the door in Figs 1 and 3 are shown to be relatively thick and the bosses 9 are made relatively smaller in order to provide space between the bosses and the 10 flanges, within which the door may be coiled.

In Fig. 4, the door b' is shown to be composed of thinner slats, and the bosses 9^a are of greater diameter than the bosses in the 15 supports of the previously described figures. With the thinner slats, less space is required between the bosses and the flanges, within which to coil the door, and the thin flexible door coils more readily about the larger 20 bosses than it would about the smaller bosses. In Fig. 4, the boss 9^a of the support c² is composed of a metal disk, secured centrally to the base 7^a by a pin or rivet 14.

In Fig. 5, I have shown a modified form 25 of support c³, in which the central boss 9^b is in the form of a roller suitably secured to the center of the base 7^b, as by a pin 15 riveted to the base.

It will be seen that the improved door 30 supports occupy a small space and that by their use the door may be coiled in a compact manner in the front part of the casing immediately above the doorway, leaving the space at the rear of the supports clear so 35 that a flour bin may, if desired, be extended through the top of the casing, or the space at the rear of the supports may be otherwise utilized.

After the door has been raised until its 40 lower end is somewhat above the center of the doorway and its upper end has coiled upon itself about the bosses in the supports, the friction of the slats on the bosses is sufficient to prevent the door from falling by 45 gravity to its closed position. Thus, no auxiliary devices are required to support the door in its raised position.

What I claim is:

1. The combination with a casing having 50 a doorway, grooves at the sides of the doorway and a door composed of flexibly connected slats slideable in said grooves, of door supports at the upper ends of the grooves, each support comprising a flat plate having 55 an arcuate flange the ends of which are arranged at opposite sides of the adjacent groove, and having a projection on its face within and spaced from the flange and

adapted to co-operate with the latter to cause the door to coil within the support when the 60 door is raised.

2. The combination with a casing having a doorway, grooves at the sides of the doorway and a door composed of flexibly connected slats slideable in said grooves, of door supports at the upper ends of the grooves, each support comprising a flat plate having a central boss and a surrounding arcuate flange spaced from the boss to permit the 65 door to coil between the flange and boss, the 70 ends of the flange being arranged at opposite sides of the adjacent groove.

3. The combination with a casing having a doorway, inner and outer strips at each 75 side of the doorway, forming grooves, the inner strips being shorter than the outer strips, and a door composed of flexibly connected slats slideable in said grooves, of door supports at the upper ends of the grooves, each support comprising a flat plate having a central boss and a surrounding arcuate flange spaced from the boss to permit the 80 door to coil between the flange and boss, the flange having one end outwardly turned and terminating over the inner strip of the adjacent groove and having its other end extended 85 across the groove.

4. Supporting means for doors composed of flexibly connected slats, comprising a metal disk having an arcuate flange extending around the greater part of its circumference and having a central boss spaced from the flange a sufficient distance to permit the 90 edge of the door to be coiled between the boss and the flange. 95

5. Supporting means for doors composed of flexibly connected slats, comprising a metal disk having an arcuate flange extending around the greater part of its circumference and having a central boss spaced from the flange a sufficient distance to permit the 100 edge of the door to be coiled between the boss and the flange, one end of the flange being turned outwardly.

6. Supporting means for doors composed of flexibly connected slats, comprising a metal disk having an arcuate flange extending around the greater part of its circumference and having a central boss, struck up 105 from the body of the disk, spaced from the flange a sufficient distance to permit the edge of the door to be coiled between the boss and the flange. 110

In testimony whereof I hereunto affix my signature.

AXEL I. S. HALVORSEN.
